Attorney

UNITED STATES PATENT OFFICE.

TONY DE STEFAN, OF LATTIMER MINES, PENNSYLVANIA.

NAIL-SET.

1,264,904.

Specification of Letters Patent.

Patented May 7, 1918.

Application filed December 23, 1917. Serial No. 209,264.

To all whom it may concern:

Be it known that I, TONY DE STEFAN, a citizen of the United States of America, residing at Lattimer Mines, in the county of 5 Luzerne and State of Pennsylvania, have invented certain new and useful Improvements in Nail-Sets, of which the following is a specification.

This invention relates to certain new and 10 useful improvements in nail-sets.

The primary object of the invention is the provision of a nail set adapted for operating upon the heads of nails for driving the nails into an object, the arrangement 15 being such as to prevent the fingers of the operator from being struck by the hammer and affording an enlarged surface with which the hammer may be readily contacted.

20 A further object of the device is to provide a nail set that is easy and inexpensive to manufacture, and which may be readily carried in the pocket or with a set of tools adapted for instant use in providing an intermediate member between a nail to be 25 driven and the driving hammer whereby the head of the nail may be slightly countersunk into the work if desired.

With these general objects in view and 30 others that will appear as the nature of the invention is better understood, the same consists in the novel construction, combination and arrangement of parts hereinafter more fully described, illustrated in the accompanying drawings and then claimed:

35 In the drawings forming a part of this application, and in which like reference characters refer to corresponding parts throughout the several views,

40 Figure 1 is a perspective view of the device illustrating the operation thereof and Fig. 2 is a side elevation of the device.

45 It will be understood that my invention is adapted for use wherever a nail set may be employed such for instance as the driving of nails 10 to a point flush with the upper face of the flooring boards 11 without marring the boards or counter-sinking the nails 10 slightly within the upper surface 50 of the boards if found desirable.

The nail set 12 which forms the subject matter of my invention broadly consists of a shank 13 having a finger ring 14 at one end thereof positioned laterally of the 55 said shank while a substantially cartridge-shaped anvil 15 is transversely arranged at

the opposite end of the shank 13 and lying in the same plane with the ring 14 and the longitudinal axis of the shank 13.

A substantially triangular enlargement 60 16 is positioned substantially centrally of the shank 13 extending in the plane of the longitudinal axis of the shank 13 and anvil 15 which provides a shoulder 17 opposite the said anvil. A flat striking end 18 is 65 arranged at the end of the anvil 15 adjacent the enlargement 16 while the opposite end 19 of the anvil 15 is also flat but is formed of much less area than the striking face 18 by reason of the contracting of the 70 adjacent end portion 20 of the anvil, thereby facilitating the positioning of the anvil end 19 upon a nail.

In operation, it will be understood that 75 the nail set is readily grasped in the hand of the operator by positioning the thumb within the ring 14 and resting the fore finger upon the shoulder 17 of the enlargement 16 with the shank 13 between the fore and index finger. The small end 19 of the 80 anvil 15 is held upon the nail such as 10, while a hammer, not shown, is struck upon the larger end 18 of the anvil, thereby depressing the nail 10 to the desired degree. The nail engaging end 19 is preferably of 85 less diameter than that of the head end of the nail so as to permit a suitable counterbalancing of the nail during the operation of the device.

A serviceable structure is provided by 90 means of which nails may be readily set into the work in an advantageous manner and the device possesses great strength, simplicity in structure, as well as presenting a pleasing appearance.

95 The anvil 15 is readily positioned upon the nail 10 in axial alignment therewith during the operation of the device in the manner described due to the pressure of the thumb and forefinger between the ring 15 100 105 which is a band formation and the shoulder 17, which positioning is rendered possible by the fact that the ring 14 and enlargement 16, project from one side of the shank 13 in the axial plane of the said shank and anvil.

What I claim as new is:—

1. A nail set comprising a shank, a thumb-receiving ring projecting laterally thereof at one end of the shank, a cartridge-shaped anvil transversely arranged at the 110 opposite end of the shank with its longitu-

- dinal axis in the same plane with the diameter of the ring and a centrally positioned enlargement upon the shank having a finger engaging shoulder at the side thereof adjacent the anvil and projecting from the shank in the aforementioned plane.
5. A nail set comprising a shank, a band ring and a shouldered enlargement spaced apart upon one side of the shank adapted for holding engagement by the hand of the operator and an elongated anvil transversely arranged upon an end of the shank having an enlarged striking end and a reduced nail engaging end.
10. 2. A nail set comprising a shank, a band ring and a shouldered enlargement spaced apart upon one side of the shank adapted for holding engagement by the hand of the operator and an elongated anvil transversely arranged upon an end of the shank having an enlarged striking end and a reduced nail engaging end.

3. An article of manufacture integrally 15 formed in a one-piece structure comprising a shank, a ring, a striking anvil and an intermediately positioned enlargement carried by the shank in the axial plane of the shank, the said ring and enlargement forming oppositely positioned finger engaging portions during the holding operation and the opposite ends of the anvil being adapted for seating upon a nail and for engagement by a striking member respectively.

20 In testimony whereof I affix my signature.

25 TONY DE STEFAN.

Copies of this patent may be obtained for five cents each, by addressing the "Commissioner of Patents, Washington, D. C."
